DESIGN FOR A TRUNDLE TOY

Lynn Bogue Hunt, New York, N. Y., assignor to
Fisher-Price Toys, Inc., East Aurora, N. Y.

Application May 2, 1947, Serial No. 138,783

Term of patent 7 years

(Cl. D34—15)

To all whom it may concern:

Be it known that I, Lynn Bogue Hunt, a citizen of the United States, residing at New York, in the county of New York and State of New York, have invented a new, original, and ornamental Design for Trundle Toy, of which the following is a specification, reference being had to the accompanying drawing, forming part thereof.

Fig. 1 is a side elevational view of a trundle toy, showing my design;

Fig. 2 is a top plan view thereof; and

Fig. 3 is a front end elevational view thereof.

The side of the trundle toy not shown is substantially the same as the side thereof which

is shown in Fig. 1. The dominant feature of my design resides in solid lines in the drawing.

I claim:

The ornamental design for a trundle toy, as shown and described.

LYNN BOGUE HUNT.
